UNITED STATES PATENT OFFICE.

OSCAR ROESEN, OF BROOKLYN, NEW YORK. ASSIGNOR TO R. HOE AND CO., OF NEW YORK, N. Y., A CORPORATION OF NEW YORK.

SHEET DELIVERY.

Application filed November 7, 1918. Serial No. 261,453.

To all whom it may concern:

Be it known that I, OSCAR ROESEN, a citizen of the United States, residing at borough of Brooklyn, county of Kings, and 5 State of New York, have invented certain new and useful Improvements in Sheet Deliveries, fully described and represented in the following specification and the accompanying drawings, forming a part of 10 the same.

This invention relates to certain improvements in delivery mechanism for printing machines.

In certain type of deliveries a plurality 15 of sheets are collected to produce a product of sixteen, thirty-two, etc. pages, these collected sheets being folded and then delivered. This class of product has sufficient body so that it can be readily delivered 20 with the usual stacker delivery. In some instances, however, it is desired to deliver a sheet folded once to produce a four page product. With this class of product difficulty has been experienced because such a 25 product, owing to its lightness or lack of body, renders itself liable to displacement when delivered to the stacker or other delivery, and, furthermore, because of this lightness difficulty has been experienced in 30 producing a delivery mechanism which will operate to deliver or move one product out of the way before the next incoming product is to be operated upon.

It is the especial object of the invention 35 to produce a mechanism capacitated to fold a sheet to form a light product, as a four page sheet, and to collect a plurality of such products into a bunch so that the product can be handled in the delivery and at high 40 speed.

A further object of the invention is to produce a construction in which by silencing certain parts a product collected to any desired number of pages may be folded and 45 delivered.

A further object of the invention is to produce a construction capacitated to collect a folded product and then collect such folded products into bunches and deliver 50 such bunched product.

It is a further object of the invention to produce a mechanism capacitated to handle previously cut sheets or to cut sheets from a continuous web and handle such cut web 55 sheets.

Generally speaking, the invention consists in the provision with sheet forwarding means, of a cylinder which may act both as a collecting and folding off cylinder, or simply as a folding off cylinder, and a collecting cylinder co-operating therewith for collecting a bunch of the products forwarded to it from the first cylinder, the second cylinder delivering these bunched products and the collecting mechanism of such cylinder being so arranged that, if desired, a collected product from the first cylinder 60 may be sent direct to the delivery.

For a full understanding of the invention reference may be had to the accompanying 70 drawings, which illustrate diagrammatically so much of the mechanism as is necessary for understanding the invention.

In these drawings:-

Figure 1 is a diagrammatic view of a construction in which a web may be forwarded, sheets cut therefrom, these web sheets collected and folded, if desired, and the collected and folded sheets again collected in bunches for delivery, or single web sheets 80 folded, collected in bunches and delivered.

Figure 2 is a diagrammatic view of a construction in which cut sheets may be forwarded either singly or collected and folded, and in which the folded sheets may be collected in bunches for delivery, or a collected product forwarded to delivery without second collection.

Referring now to the drawings, and first to Figure 2, a cut sheet is forwarded in any 90 suitable manner as by a pair of forwarding rolls 1, 2, the forwarding rolls forwarding the sheet to a folding and collecting mechanism which is illustrated in the form of a cylinder 3. The sheets are folded from 95 this cylinder to a pair of folding off rolls 5, 6. In the best construction this cylinder 3 will, also, be a collecting cylinder for collecting a plurality of sheets, the cylinder for this purpose being provided with sheet taking devices, such as a pair of pins 7.

It will be understood that the folding blades of cylinder 3 will be timed to operate either to fold off a single sheet or a collected product when the cylinder is being 105 used for collecting.

From the folding rolls 5, 6, where such are employed, the product is forwarded to a mechanism which may be arranged to collect a plurality of the folded sheets into 110

bunches, where a light product is to be handled, or can be arranged to act as a straight delivery to deliver a product collected by the cylinder 3, where no second collection is desired. While this mechanism may be varied within wide limits, in the particular construction illustrated, there is provided a collecting cylinder 8 with sheet taking devices arranged in sets, these sheet taking devices being used where the cylinder is employed for collecting into a bunch or signature a plurality of products delivered from cylinder 3. As illustrated, each set of these sheet taking devices includes long and short grippers 9, 10, three sets of these grippers being illustrated, these grippers acting to collect the product in the usual manner.

If it be desired to employ the cylinder simply as a forwarding cylinder, these grippers are silenced, and there are provided forwarding rolls 11, 12 co-operating with the cylinder, which act to forward the product from the folding rolls 5, 6 to the usual draw off rolls 13, from which the product is delivered to any suitable delivery, as for instance, the pusher delivery 14, illustrated.

With this construction a light folded product may be collected in bunches of such thickness that they can be handled by the delivery, or a collected product may be sent through the machine and folded, the only change in mechanism being the silencing of the gripper devices on the second collecting cylinder, and rendering operative the pins 7.

In Figure 1 there is illustrated a construction which may be employed for forwarding a web, severing sheets therefrom, and either collecting such sheets in a desired product, folding them, and delivering them, or folding single sheets, collecting such sheets in bunches, and delivering the bunches, or collecting in bunches a plurality of collected sheets, the construction shown in this figure permitting a wider range of products to be secured than in constructions specifically illustrated in Fig. 2.

Referring now to Figure 1, the web W, which like the sheets referred to in the description of Fig. 2 may come from a printing machine of any desired character, is forwarded by a pair of forwarding rolls 15, 16 to a cutting mechanism, shown as cylinders 17, 18, by which the web is severed into sheets. These cut sheets may be forwarded by a pair of forwarding rolls 19, 20, to a collecting and folding mechanism. This mechanism includes a first cylinder 21, which may be employed as a collecting cylinder, being provided with three sets of sheet taking devices, as long and short grippers 22, 23. This cylinder 21 may also operate as a folding-off cylinder, being provided with folding blades 24, folding off

either a single sheet or a plurality of collected sheets to a folding off cylinder 25 provided with folding jaws 26. It will be understood that the folding blades 24 will be timed so as to fold off single sheets or to fold off a collected product when the cylinder 21 is acting as a collecting cylinder. From the folding off cylinder 25 the folded sheet or the folded collected product is forwarded to the second collecting mechanism by which a plurality of folded single sheets or a product of folded collected sheets may be collected for final delivery. This mechanism is illustrated in the form of a cylinder 27, provided with collecting devices in the form of long and short sheet taking grippers 28, 29. From this cylinder the product is finally delivered to any suitable delivery, as a stacker delivery 30, similar to delivery 14, before referred to. 85

In the construction illustrated in this figure, a wide variety of products may be obtained and delivered. If a single collected product from cylinder 21 is to be delivered, the collecting grippers of cylinder 27 are silenced and the collected folded product delivered. If, however, folded single sheets are desired as a final product, these sheets are folded as described and collected on the cylinder 27, and the bunch of folded sheets 95 delivered. If it be desired to produce a large product, both cylinder 21 and cylinder 27 may be operated in their collecting capacity, a product being collected on cylinder 21 and a plurality of such collected 100 products being collected on cylinder 27, and then delivered.

While the invention is shown in its preferred form, it will be understood that various changes may be made in the specific 105 mechanisms for carrying out the invention, and that by changing the sheet taking devices on the different collecting cylinders a wide range of products may be obtained, and the invention is not restricted to the precise 110 arrangement or operation of these collecting cylinders.

What is claimed is:

1. In a delivery for handling light sheets, the combination of means for forwarding 115 single sheets, a cylinder to which the sheets are forwarded capacitated to fold and forward single sheets with one fold or fold and forward a plurality of collected sheets, a second cylinder cooperating with the first cylinder and capacitated to superpose a plurality of single folded sheets to form a pack or bunch, or to deliver directly a folded collected product, and a stacker delivery to which the packs are delivered side by side. 120

2. In a delivery, the combination of means for forwarding a sheet, means for collecting a plurality of sheets, means for folding the collected sheets, and means for collecting a plurality of the collected folded sheets prior 130

to delivery to which the collected and folded sheets are transferred, said means including devices for positively seizing and holding the sheets during transfer and collecting.

5 3. In a delivery, the combination of web forwarding means, means for severing the web into sheets, means for collecting a plurality of the severed sheets, means for folding the collected sheets, and means for collecting a plurality of the collected and folded sheets prior to delivery to which the collected and folded sheets are transferred, said means including devices for positively seizing and holding the sheets during transfer

15 and collecting.

4. In a delivery, the combination of web forwarding means, cutting mechanism for severing the web into sheets, sheet forwarding means, a collecting cylinder for collecting a plurality of cut sheets, folding devices for folding the collected sheets, a collecting cylinder to which the collected and folded sheets are transferred for collecting a plurality of the collected folded sheets, and

25 means for seizing and holding the sheets during transfer and collecting.

5. The combination of cutting mechanism and sheet forwarding means, a collecting cylinder for collecting a plurality of cut sheets, folding devices for folding the collected sheets, a collecting cylinder to which the collected and folded sheets are transferred for collecting a plurality of the collected folded sheets, means for seizing and holding the

35 collected and folded sheets during transfer and second collection, and a delivery.

6. The combination with sheet forwarding devices, of a folding and collecting cylinder provided with sheet taking devices, a second collecting cylinder provided with sheet taking devices for collecting the product of the first cylinder in bunches to which the product of the first cylinder is forwarded, means for positively seizing and holding the

45 product during transfer from the first cylinder to the second cylinder, and a delivery.

7. In a delivery for light products, the

combination of means for forwarding single sheets, a cylinder to which the sheets are forwarded capacitated to fold and forward 50 single sheets with one fold, or fold and forward a plurality of collected sheets, a transfer cylinder provided with folding jaws for taking a product from the folding and collecting cylinder, and a second folding or collecting cylinder taking a product from the transfer cylinder and capacitated to superpose a plurality of single folded sheets to form a pack or bunch for delivery, or to deliver directly a folded collected product. 60

8. In a delivery for handling light products, the combination of means for forwarding single sheets, a cylinder to which the sheets are forwarded capacitated to fold and forward 65 single sheets with one fold or fold and forward a plurality of collected sheets, a transfer cylinder provided with folding jaws for taking the product from the folding and collecting cylinder, a second folding and collecting cylinder taking a product from the transfer cylinder and capacitated to superpose a plurality of single folded sheets to form a pack or bunch for delivery, or to deliver directly a folded collected product. 70

9. In a delivery for light products, the combination of means for forwarding single sheets, a cylinder to which the sheets are 80 forwarded capacitated to fold and forward single sheets with one fold, or fold and forward a plurality of collected sheets, and a second cylinder co-operating with the first cylinder and capacitated to superpose a 85 plurality of single folded sheets to form a pack or bunch for delivery or to deliver directly a folded, collected product.

In testimony whereof, I have hereunto set my hand.

OSCAR ROESEN.
